[57] CLAIM

The ornamental design for a chair, as shown and described.

DESCRIPTION

FIG. 1 is a left side elevational view of a chair showing my new design, the right side being a mirror image thereof;

FIG. 2 is a top plan view;

FIG. 3 is a front elevational view;

FIG. 4 is a rear elevational view; and,

FIG. 5 is a bottom plan view thereof.

Fig. 3

A handwritten signature or mark, possibly 'S. 5'.
